DESIGN FOR A GARMENT HANGER

Philip W. Leifer and Peter A. Katz,
New York, N. Y.

Application December 15, 1944, Serial No. 116,908

Term of patent 7 years

(Cl. D80—8)

To all whom it may concern:

Be it known that we, Philip W. Leifer and Peter A. Katz, both citizens of the United States of America and residing respectively at New York city, in the county and State of New York, and at New York city, in the county of Kings and State of New York, have invented a new, original, and ornamental Design for a Garment Hanger, of which the following is a specification, reference being had to the accompanying drawing, forming a part thereof.

Fig. 1 is a front elevation of a garment hanger, showing our new design.

Fig. 2 is a top plan view thereof.

Fig. 3 is a fragmentary sectional view thereof taken on line 3—3 of Fig. 1, and

Fig. 4 is a sectional view thereof taken on line 4—4 of Fig. 1.

The dominant feature of the design resides in the portions shown in full lines.

We claim:

The ornamental design for a garment hanger, substantially as shown and described.

PHILIP W. LEIFER.
PETER A. KATZ.
